UNITED STATES PATENT OFFICE.

ISADOR RUDOLPH, OF PHILADELPHIA, PENNSYLVANIA.

DESIGN FOR A FLAG OR BANNER.

56,384.

Specification for Design.

Patented Oct. 5, 1920.

Application filed April 25, 1918. Serial No. 230,812. Term of patent 7 years.

To all whom it may concern:

Be it known that I, ISADOR RUDOLPH, a citizen of the United States, residing at Philadelphia, in the county of Philadelphia and State of Pennsylvania, have invented a new, original, and ornamental Design for Flags or Banners, of which the following is a specification, reference being had to the accompanying drawing, forming a part thereof.

The figure is an elevational view of a flag or banner, showing my new design.

I claim:

The ornamental design for a flag or banner, as shown.

ISADOR RUDOLPH.
